UNITED STATES PATENT OFFICE.

MAX STRAKOSCH, OF VIENNA, AUSTRIA-HUNGARY, ASSIGNOR TO JULIUS HOFMEIER, OF SAME PLACE.

ACETYLENE-GAS LAMP.

SPECIFICATION forming part of Letters Patent No. 628,964, dated July 18, 1899.

Application filed April 25, 1899. Serial No. 714,404. (No model.)

To all whom it may concern:

Be it known that I, MAX STRAKOSCH, residing at Vienna, Austria-Hungary, have invented a certain new and useful Improved 5 Acetylene-Lamp, of which the following is a specification.

Acetylene-lamps of present construction suffer, among other disadvantages, from the inconvenience of having to clear the carbid- 10 reservoir of the carbid residues, this having hitherto been done in a very incomplete and tedious manner by means of a cloth.

The present invention has for its object to enable the carbid-reservoir to be cleared rapidly 15 in a perfect and simple manner, this being done by means of a piston, by the motion of which by hand or by spring power the carbid residues are removed from the reservoir.

The accompanying drawings show the construction 20 of an acetylene-lamp according to my said invention.

Figure 1 shows a vertical section of the lamp, and Fig. 2 a horizontal section.

The carbid-receptacle 1 is closed at its lower 25 end by a hinged bottom 2, and it contains a perforated piston 3, whose rod 4 passes through a tube 5 of the water-reservoir 6 to the outside, where it is provided with a pressing-knob 7. In place of the piston-rod may be 30 employed a helical spring 8, (indicated by dotted lines,) which presses at top against the bottom of the water-reservoir and at bottom against the piston.

The carbid is introduced in the form of a 35 cartridge 9, which is preferably made of non-waterproof material, such as blotting-paper, and is made of rectangular form, so that it can expand in the circular generating-chamber. The cartridge is held down upon the 40 bottom of the receptacle by the piston 3 either by the pressure of the spring or by the fric-

tion of the piston-rod 4 in the stuffing-box at top. The cartridge is thus held securely in position.

When the spent carbid residue is to be removed, the bottom 2 is opened and the piston 3 is forced downward, whereby the cartridge is forced out and at the same time the chamber is cleared, so that only the under side of the piston requires to be wiped with a cloth. 45 If the spring 8 is used, this will automatically force out the spent cartridge on opening the bottom. 50

For keeping the upper surface of the piston as clean as possible it is advisable to provide it with only a few perforations for allowing the water to gain access to the carbid. In place of the perforated piston may also be used a non-perforated piston that does not fit very tight in the chamber, in which case the 55 water will find its way to the carbid through the interstices between the piston and the cylinder.

Having thus particularly described and ascertained the nature of this invention and the 60 best means I know for carrying the same into practical effect, I claim—

In combination, the lamp-body having a water-compartment in its upper portion and a gas-generating chamber beneath the same, a 65 removable bottom to said gas-generating chamber, and a carbid-expelling piston in said chamber having a piston-rod extending up through the water-compartment to the top of the lamp, substantially as described. 70

In testimony whereof I have hereunto set my hand in presence of two subscribing witnesses.

MAX STRAKOSCH.
